(57) **CLAIM**

The ornamental design for a spinning sign assembly, as shown and described.

DESCRIPTION

FIG. 1 is a front, right perspective view of a spinning sign assembly, according to an embodiment of the present invention;

FIG. 2 is a front view of the spinning sign assembly of FIG. 1; FIG. 3 is a left side view of the spinning sign assembly of FIG. 1;

FIG. 4 is a rear view of the spinning sign assembly of FIG. 1; FIG. 5 is a right side view of the spinning sign assembly of FIG. 1;

FIG. 6 is a bottom view of the spinning sign assembly of FIG. 1;

FIG. 7 is a top view of the spinning sign assembly of FIG. 1; FIG. 8 is a front, right perspective view of a spinning sign assembly, according to another embodiment of the present invention;

FIG. 9 is a front view of the spinning sign assembly of FIG. 8; FIG. 10 is a left side view of the spinning sign assembly of FIG. 8;

FIG. 11 is a rear view of the spinning sign assembly of FIG. 8;

FIG. 12 is a right side view of the spinning sign assembly of FIG. 8;

FIG. 13 is a bottom view of the spinning sign assembly of FIG. 8; and,

FIG. 14 is a top view of the spinning sign assembly of FIG. 8. The broken lines adjacent to the shaded surfaces represent the boundaries of the claimed design and form no part thereof. All other broken lines illustrate environmental detail and form no part of the claimed design.
